GAME HOUSE

Göteborg Klara Maria Jaros, Fördärlagsgatan 5,
S-415 06 Göteborg, Sweden

Filed June 6, 1974, Ser. No. 476,371

Term of patent 14 years

Int. Cl. D21—01

U.S. Cl. D34—15 LL

FIG. 1

FIG. 2

FIG. 3

FIG. 4

FIG. 5

FIG. 6

FIG. 1 is a rear perspective view of a game house showing my new design on an enlarged scale;

FIG. 2 is a left side elevational view thereof;

FIG. 3 is a right side elevational view thereof;

FIG. 4 is a front elevational view thereof;

FIG. 5 is a right front perspective view of another embodiment of my new design of FIG. 1;

FIG. 6 is a left side elevational view thereof;

FIG. 7 is a rear elevational view thereof;

I claim:

The ornamental design for a game house, substantially as shown and described.

FIG. 7
